JAMES H. PORTER, OF NEW YORK, N. Y., ASSIGNOR TO FREDERIC H. NORTH, OF NEW BRITAIN, CONNECTICUT.

Letters Patent No. 71,640, dated December 3, 1867.

IMPROVEMENT IN ADJUSTABLE TUMBLERS FOR PERMUTATION LOCKS.

The Schedule referred to in these Letters Patent and making part of the same.

TO ALL WHOM IT MAY CONCERN:

Be it known that I, JAMES H. PORTER, of the city and State of New York, have invented, made, and applied to use, a certain new and useful Improvement in Locks; and I do hereby declare the following to be a full, clear, and exact description of the said invention, reference being had to the annexed drawing, making part of this specification, wherein—

Figure 1 is a side view of one of the lock-tumblers to which my invention relates, a portion of one side being shown sectionally, and

Figure 2 is a sectional view at the line $z z$.

Similar marks of reference denote the same parts.

My invention relates to the peculiarity of construction of a circular tumbler employed in that class of locks where a series of circular tumblers is used, the said tumblers having each a notch in its periphery, and the tumblers being set successively to the proper point denoted by an index outside the lock, so that the stud of the bolt can pass into said notches as the bolt is withdrawn. I make each of said circular tumblers in three principal parts, the first being a disk carrying a stud, the second a half circle, with a mortise hinged to the third piece, which is a similar half circle, but it has a tongue that passes into the said mortise; and an eccentric or cam is fitted so as to draw the tongue farther into the mortise, and clamp the stud-disk between the half circles forming the lock-tumbler. In the lock-tumbler the usual notch to receive the stud of the bolt is provided, and, by turning the eccentric or cam into such a position that the stud-disk will be relieved of the clamping friction of the tumbler, the said disk can be turned, in order that the position of its stud relatively to the notch in the tumbler may be varied, and thereby change the points of indication for opening the lock.

In the drawing, *a* is the axis on which the tumblers are rotated; *b* is the disk, and *c* its stud; *d* and *e* are the half circles, hinged together at *f*, and forming the tumbler. In the half tumbler *d* is a mortise, covered by the removable cap-plate *i*, and *o* is a tongue on the half, *e*, of the tumbler, entering the mortise in *d*, and having a hole elongated for the reception of the eccentric or cam *l*, the hubs of which occupy holes at the sides of the mortise in *d*; and said cam or eccentric has a polygonal hole through it for the reception of a key, by means of which the eccentric may be turned to relieve the disk *b*, or to clamp it firmly between the halves *d e* forming the circular tumbler.

What I claim, and desire to secure by Letters Patent, is—

The circular tumbler *d e*, formed of two parts hinged together, in combination with the disk *b*, and with mechanism, substantially as specified, for drawing the parts of the tumbler together and clamping said disk, as set forth.

In witness whereof, I have hereunto set my signature, this fifteenth day of June, A. D. 1867.

J. H. PORTER.

Witnesses:
